PRINTING PRESS AND THE LIKE

Leroy Q. Presby, Melrose, Mass., assignor to
 American Stay Company, East Boston, Mass.,
 a corporation of Massachusetts

Application December 7, 1939, Serial No. 307,994

22 Claims. (Cl. 101—181)

My invention relates to printing presses or the like, that is to say, apparatus for applying to a web ink, colors, or uncolored liquid material to form on the web printed characters, designs, coatings and the like as the case may be. The invention is particularly applicable to so-called multi-color printing presses.

The invention will be best understood from the following description when read in the light of the accompanying drawings of an embodiment of the invention, the scope of which latter will be more particularly pointed out in the appended claims.

In the drawings:

Fig. 1 is a diagram showing a four color printing press with the web threaded through it in such way as to apply ink or the like to the same side of the web in each printing couple;

Fig. 2 is a diagram of the same press as Fig. 1 with the web threaded through it in such way that the first printing couple applies ink or the like to one side of the web, while the remaining three printing couples all apply it to the opposite side of the web;

Fig. 3 is a further diagram of the press according to Fig. 1 with the web threaded through it in such way that the first two printing couples apply ink or the like to one and the same side of the web, while the remaining two printing couples apply it to the opposite side of the web;

Fig. 4 is a vertical longitudinal section, on an enlarged scale, of the left hand end portion of a press according to Fig. 1 taken along its medial line, with parts omitted and parts shown more or less diagrammatically;

Fig. 5 is an elevation, on an enlarged scale, of a fragment of the left hand end of the press according to Fig. 1, with parts omitted and parts shown more or less diagrammatically;

Fig. 6 is a longitudinal medial section, on an enlarged scale, with parts in elevation, of one of the driers for the web;

Fig. 7 is a bottom view of the upper air chamber of the drier according to Fig. 6, corresponding to a section on the line 7—7 of Fig. 6, with parts omitted;

Fig. 8 is a plan of a fragment of the lower air chamber of the drier according to Fig. 6, corresponding to a section on the line 8—8 of Fig. 6, with parts omitted;

Fig. 9 is a section on the line 9—9 of Fig. 6;

Fig. 10 is an elevation, on an enlarged scale, showing the gear shift and shiftable doctor knife mechanisms for the reversible printing couples; and

Fig. 11 is a section on the line 11—11 of Fig. 10.

In the press diagrammatically shown by Fig. 1 each printing couple comprises a print roll 1 and an impression roll 2, the print roll, which may be a rotogravure cylinder, dipping into an ink or other fountain (not shown) so as to supply ink or the like to the web W as it passes between the print and impression rolls. The web is unwound from a roll of web 5, and after being fed through the printing couples in series is wound into a roll 1, the printing couples and driving mechanism for the rewind reel acting to feed the web. It will be understood, however, that the "print roll" may be of any suitable type to apply ink or coating material to the web whether to print characters on it or coat it.

As shown, associated with the printing couple adjacent the roll of web 5 are a pair of web supporting and guide rolls 9 and a second pair 11, while associated with a movable drier 13 for receiving the web as it comes from this first printing couple is a roller 15. By use of the two rollers 9 the web may be so threaded through the apparatus to pass it through the printing couple as shown in Fig. 1, or by use of the pair of rollers 11 and roller 15 may be so threaded through the apparatus to pass it through the printing couple as shown in Fig. 2. As in each instance the print roll applies material to the lower side of the portion of the web contacting it, the side of the web printed by this couple in Fig. 2 is opposite that printed in Fig. 1.

As is hereinafter more fully described, the printing couple adjacent the roll of web 5, and the next successive couple, are each provided with a reverse mechanism for driving it in either of opposite directions, and are further provided with doctor knives 17 and 19 which may be selectively employed. As shown in Fig. 1, the extreme right hand printing couple is rotated counter-clockwise, as indicated by the associated arrow, and only the doctor knife 17 cooperates with it. As shown in Fig. 2, the same printing couple is rotated clockwise, as indicated by the arrow, and only the doctor knife 19 cooperates with it.

The right hand drier 13 shown in Fig. 1 has associated therewith a roller 21 about which the web passes as it leaves the drier, and associated with the second printing couple from the right as viewed in Fig. 1 are a roller 23 and a pair of rollers 25, while associated with the drier 13 for the portion of the web printed by this second printing couple is a second roller 15. By use of the rollers 21 and 23 the web may be passed through the second printing couple from right

to left, as shown in Fig. 1, to print one side of the web, or by use of these same rollers and the pair of rollers 25 and the roller 15 may be passed through the printing couple from left to right, as shown in Fig. 3, to print its opposite side.

The web after leaving the second drier 13 passes over second rollers 24 and 23 through the third printing couple to a drier 21. Leaving this drier it is guided by the rollers 29 and 31 through the fourth printing couple. Leaving the fourth printing couple it passes through a drier 33 and is finally rewound at 7. These third and fourth printing couples need not be reversible and need be provided with but one doctor knife.

It will be observed that each printing couple prints on the under side of the portion of the web passing through it, and that therefore by having the first two printing couples reversible the apparatus illustrated can print four colors or the like on one side of the web, as shown by Fig. 1, or one color on one side and three on the opposite side, as shown by Fig. 2, or two colors on one side and two on the opposite side, as shown by Fig. 3.

The general arrangement of mechanism and construction of the driers is as shown in applicant's co-pending application Serial Number 286,826, filed July 27, 1939, and therefore need not be described with any more particularity than necessary to explain the present invention.

As more fully illustrated in Figs. 5 to 9, the two driers 13 each comprise a casing 35 provided at each end with a slot 37 for entrance and exit respectively of the web. At the bottom of the casing is an elongated air chamber 39 having an upper generally concave face 41, while at the upper portion of the casing is an elongated air chamber 43 having a lower generally concave face 45. Distributed along the faces 41 and 45 are transversely extending slots 47 for discharge of air against the web, air being forced into the air chambers by separate blowers 49 driven by electric motors 51, the air entering the chambers being heated by suitable means, such as electric heating elements 53, so that the web will be acted upon by heated air.

In the space between the two air chambers of the driers 13 are upper pairs of rollers 55 and lower pairs of rollers 57. The lower pair is employed when the web is run through the driers in the way shown in Fig. 1, and the upper pair is employed when the web is run through the driers in the way shown in Fig. 3, while, as shown in Fig. 2, the upper pair of rollers is employed in the right hand drier 13, and the lower pair of rollers in the adjacent drier 13. In each of these arrangements the web has that side thereof which is printed by the immediately preceding printing couple exposed to a draft of air, while the rollers contact with the unprinted side so as not to smear the wet ink. The motors 51 may be, and preferably are, operated selectively to direct air only against the side of the web printed by the immediately preceding couple.

As illustrated in Figs. 4 and 5, each drier 13 and 27 is pivotally supported at one end at 59 upon the frame 61 above the printing couples. Each drier may be swung vertically about its pivotal support by means of a rack 63 which is pivotally connected at its lower end to the drier and meshes with a gear pinion (not shown) on a shaft 65 rotatably carried by the frame 61, this shaft being manually rotated by a hand-wheel 67. The details of the mechanism for adjustably swinging the driers about their pivotal

supports 59 do not form part of the subject matter of this application, and therefore will not be further described. This mechanism, however, may be identical with that described in my above mentioned co-pending application.

As illustrated in Figs. 5 and 6, the roller 21, hereinbefore referred to, at the exit end of each drier is carried by the latter. At the entrance end of each drier is a roller 69 carried by the drier which is employed for guiding the web when it contacts with the lower rollers 57. It will be observed that when the parts are in the position shown by Figs. 1 and 5 the roller 69 for the drier 13 contacts with the upper side of the web. However, when the opposite side of the web is to be printed, as shown at the first couple of Fig. 2, the drier is swung upwardly properly to position the roller 15 with relation to the couple, and this moves the roller 69 out of the path of the web so that its wet printed side is not contacted by that roller. This arrangement is also illustrated in Fig. 6 in which the web W when in its full line position contacts with the roller 69, but when in its dotted line position is out of contact therewith.

In the drier 27 the upper air chamber 43 is omitted, but the lower air chamber 39 is retained, as is indicated in Fig. 4. Otherwise in all significant respects its construction is like that of the drier 13, and may be identical with that described in my above mentioned co-pending application.

The drier 33, as illustrated, is generally like that shown in my above mentioned co-pending application. As shown, it comprises an elongated casing 71 (Figs. 4 and 5), at the upper portion of one end of which is positioned an elongated air chamber 73 the lower wall of which is provided with transverse slots 47, like those heretofore described, for directing heated air against the side of the web which has been printed in the last printing couple, air being forced into this chamber by means of a further blower 49 driven by a further electric motor 51, and the web being guided by rollers 74.

As illustrated, the casing of each of the driers 13 and 27 at its uppermost portion has an air discharge opening 76 connected by a conduit 77 to an adjacent opening 79 in the lower wall of the casing 71 of the drier 33. This conduit is of flexible material so as to permit the driers 13 to be adjusted vertically about their pivotal supports 59 to accommodate the driers to print rolls 1 of different diameters, and for adjusting the positions of the rollers 15 and 69 of the driers 13. An exhauster 81 driven by an electric motor 83 is connected by a conduit 85 to an opening 87 (Fig. 4) in the upper portion of the casing 71 for exhausting air from the casings of all the driers, so as to minimize or prevent discharge of air from the casing openings, as more fully explained in my above mentioned co-pending application.

The arrangement for driving the printing couples may be similar to that shown in applicant's Patent 2,107,647, February 8, 1938, and therefore need not be further explained than necessary to show how it is adapted to the present invention.

Referring particularly to Figs. 5, 10 and 11, a common drive shaft 89 for all the couples extends lengthwise of the apparatus and is supported against longitudinal movement on the frames 91 for the several printing couples. Splined to the shaft at each of the printing couples is a worm

93 (Fig. 10), the opposite ends of which are closely embraced by the arms 94 of a yoke 95 slidably supported on the shaft for movement longitudinally thereof, the yoke being so moved and held in adjusted positions by a screw 97 which can be rotated by a handwheel 99. The screw is rotatably mounted on the frame 91 in such way as to be held against longitudinal movement and is screw-threaded through a lug 101 integral with the yoke 95. Rotation of the shaft 89 therefore is effective to rotate all the worms simultaneously, but each worm may be adjusted independently of the other longitudinally of the shaft by rotation of the handwheel 99 associated with the worm for registering the colors or the like printed by the several couples.

As shown in Figs. 10 and 11, the frame 91 carries a fixed spindle 103 on which is rotatably mounted a worm wheel 105 meshing with the associated worm 93. Fixed to the worm so as to rotate therewith is a gear wheel 107, with which latter mesh gear wheels 109 and 111 positioned respectively at opposite sides of the spindle 103. The gear wheels 109 and 111 are of the same pitch diameter, and are rotatably mounted on spindles 113 fixedly carried by a lever 115 mounted for swinging on the spindle 103. Also carried by this lever is a third spindle 113 on which is rotatably mounted a gear wheel 117 of the same pitch diameter as the gear wheels 109 and 111. As shown in Fig. 10, the gear wheel 117 meshes with the gear wheel 119 fixedly carried by the shaft 121 for the adjacent print roll 1, the gear wheel 109 being out of mesh with the gear wheel 119. By swinging the handle portion 123 of the lever 115 upwardly, as viewed in Fig. 10, the gear wheel 117 will be moved out of mesh with the gear wheel 119, and the gear wheel 109 will be moved into mesh with the gear wheel 119. As the shaft 89 rotates the gear wheels 109 and 117 in opposite directions, the last mentioned movement of the lever 115 will be effective to cause the print roll to rotate in the opposite direction to that in which it is rotated with the parts in the position shown by Fig. 10. Shifting the worm longitudinally of the shaft 89 may be availed of when the shaft is not rotating to turn the gear wheels 109 and 117 slightly so as to position them to mesh properly with the gear wheel 119 when the gears are shifted. When the shaft 89 is rotating, sliding the worm longitudinally of the shaft may be availed of for properly registering the different colors or other matter applied to the web by the several couples. As shown, for securing the lever 115 in its adjusted positions it is provided with a slotted portion 125 through which extends a clamping bolt 127 threaded into the frame 91.

It will be understood that as the third and fourth couples need not be reversed the gear shift mechanism may be omitted at those couples, in which case the gear wheels 111 and 117 may be omitted and the gear wheel 109 may be permanently in mesh with the gear wheel 119.

The mechanism for each of the spring pressed doctor knives 17 and 19, as illustrated in Fig. 10, is carried by horizontally slideable blocks 129 mounted on the frame members 91 for the printing couples. These blocks may be slid horizontally by means of rotatable screws 131 turned by handwheels 133 so as selectively to move one or the other doctor knives into cooperation with the print roll. As the specific details of this mechanism form no part of the present invention it is

believed that further description of the same is unnecessary.

It will be understood that, within the scope of the appended claims, wide deviations may be made from the forms of the invention herein described without departing from the spirit of the invention.

I claim:

1. Printing apparatus or the like having, in combination, a rotary member for applying ink or the like to a web, means for selectively driving said rotary member in either of opposite directions, a drier for operating upon the web after operation thereon by said rotary member, and web supporting means for so guiding the web as to present it successively to said rotary member and drier, said supporting means being arranged to guide the web along selected paths for causing either side of the web to be selectively operated upon by said rotary member and for supporting the web when presented to said drier at its side opposite that operated upon by said rotary member.

2. Apparatus according to claim 1 in which the web supporting means is so arranged that the web may be moved in the same direction when presented to said drier independently of which side of the web is operated upon by said rotary member.

3. Apparatus according to claim 1 in which the web supporting means comprises a group of supporting rollers associated with said rotary member and a group thereof associated with said drier, which rollers of said groups are so arranged that the web may travel through different paths both when presented to said rotary member and when presented to said drier, the group of rollers associated with said drier being arranged to engage with one or the other side of the web, whereby the web may be passed in the same direction when presented to said drier independently of which side of the web is operated upon by said rotary member.

4. Apparatus according to claim 1 in which the drier has means for causing a draft of air over the side of the web operated upon by the rotary member.

5. Apparatus according to claim 1 in which the web supporting means is so arranged that the web may be moved in the same direction when presented to said drier independently of which side of the web is operated upon by said rotary member, and the drier has means for causing a draft of air over the side of the web operated upon by the rotary member.

6. Apparatus according to claim 1 in which the web supporting means is so arranged that the web may be moved in the same direction when presented to said drier independently of which side of the web is operated upon by said rotary member; and the drier has means positioned at opposite sides of the path of the web for directing drafts of air toward the web, the means at either side of the web being operable to the exclusion of the means at the other side.

7. Apparatus according to claim 1 in which the web supporting means comprises a web supporting element carried by the drier, the drier being bodily adjustable for positioning said element.

8. Apparatus according to claim 1 in which the web supporting means comprises a group of supporting rollers associated with said rotary member and a group thereof associated with said drier, which rollers of said group are so arranged

that the web may travel through different paths both when presented to said rotary member and when presented to said drier, the group of rollers associated with said drier being arranged to engage with one or the other side of the web, whereby the web may be passed in the same direction when presented to said drier independently of which side of the web is operated upon by said rotary member, said group of rollers associated with said drier being carried thereby, said drier being bodily adjustable for positioning said rollers of said group in proper relation to the path through which the web is to be guided.

9. Apparatus according to claim 1 in which the web supporting means comprises a group of supporting rollers associated with said rotary member and a group thereof associated with said drier, which rollers of said groups are so arranged that the web may travel through different paths both when presented to said rotary member and when presented to said drier, the group of rollers associated with said drier being arranged to engage with one or the other side of the web, whereby the web may be passed in the same direction when presented to said drier independently of which side of the web is operated upon by said rotary member, said drier having a roller over which the web passes when one side thereof is operated upon by said rotary member, the drier being bodily adjustable for causing said roller to be out of contact with the web when the opposite side thereof is operated upon by said rotary member.

10. Apparatus according to claim 1 in which the web supporting means is so arranged that the web may be moved in the same direction when presented to said drier independently of which side of the web is operated upon by said rotary member, the drier comprising elongated chambers at opposite sides respectively of the path of travel of the web provided with slots for discharging air from the chambers toward the web, and means for supplying air to said chambers.

11. Apparatus according to claim 1 in which the web supporting means is so arranged that the web may be moved in the same direction when presented to said drier independently of which side of the web is operated upon by said rotary member, the drier comprising elongated chambers at opposite sides respectively of the path of travel of the web provided with slots for discharging air from the chambers toward the web, and means for supplying air to said chambers having provision for supplying air to each to the exclusion of the other.

12. Printing apparatus or the like having, in combination, at least two spaced rotary members for successively applying ink or the like to a web, means for driving said rotary members having provision for driving one of them selectively in either of opposite directions for conditioning that rotary member to operate upon one or the other side of the web, web drying means for operating upon the web after operation thereon by each of said rotary members, and web supporting means for guiding the web to present it to said rotary members and web drying means; said supporting means having provision for so guiding the web along selected paths as to cause said rotary members either both to operate upon the same side of the web or one to operate upon one side and the other upon the opposite side, and to support the portion of the web coming from that rotary member which may be driven in either of

opposite directions at the side of the web opposite the selected side thereof operated upon by such rotary member.

13. Apparatus according to claim 12 in which the web drying means comprises separate driers for the portions of the web coming from each of said rotary members respectively, the drier for the portion which comes from the rotary member which may be driven in either of opposite directions carrying an element of the web supporting means and being bodily adjustable for positioning that element.

14. Apparatus according to claim 12 in which the web drying means comprises separate driers for the portions of the web coming from each of said rotary members respectively, said driers each having means for passing a draft of air over the side of the web which has been operated upon by the associated rotary member.

15. Apparatus according to claim 12 in which the web drying means comprises separate driers for the portions of the web coming from each of said rotary members respectively, said driers each having means for passing a draft of air over the side of the web which has been operated upon by the associated rotary member, the drier associated with the rotary member which may be driven in either of opposite directions having means which may be operated to pass a draft of air selectively over either side of the web to the exclusion of the other.

16. A printing press having, in combination, cooperating print and impression rolls, a rotary drive shaft, a worm on said shaft driven thereby, a worm wheel meshing with said worm, a first gear coaxial with said worm wheel for rotation therewith, a member mounted for swinging movement about the axial line of said coaxial worm wheel and first gear, a second gear coaxial with said print roll for rotating it, said member carrying gearing permanently in driven relation to said first gear comprising a third gear rotated in one direction and a fourth gear rotated in the opposite direction, which third and fourth gears are so mounted upon said member that swinging of the latter into one position is effective to mesh said third gear with said second gear to the exclusion of said fourth gear, and swinging it into another position is effective to mesh said fourth gear with said second gear to the exclusion of said third gear, said worm being adjustably slidable along said shaft for rotating said third and fourth gears.

17. A printing press having, in combination, 55 cooperating print and impression rolls, a rotary drive shaft, gearing for connecting said drive shaft to said print roll comprising shiftable reverse gearing for causing said shaft to drive said print roll in either of opposite directions; said 60 gearing comprising a gear in permanent driven relation to said shaft, a gear in permanent driving relation to said print roll, a third gear and a fourth gear both in permanent operative relation to one of said first mentioned gears and bodily shiftable about the axis of that gear for meshing said third and fourth gears selectively with the other of said first mentioned gears, said gear which is in permanent driven relation to said shaft being adapted to drive said third and fourth gears respectively in opposite directions, and means for angularly adjusting, relative to said shaft, said gear which is in permanent driven relation to said shaft.

18. A printing press according to claim 17 in which the third and fourth gears are carried

by a single member which is movable for selectively meshing them with the gear specified by claim 17.

19. A drier for a web having a casing provided with openings for entrance and exit of the web, elongated spaced chambers in said casing in spaced relation to form a space through which the web is passed, means for supporting the web in said space at one or the other side of the web, each chamber being provided with distributed openings for directing air against the web, means for forcing air into said chambers having provision for forcing it into each to the exclusion of the other, and means for withdrawing air from said casing for minimizing discharge of air through the casing openings.

20. A printing press having, in combination, cooperating print and impression rolls, a rotary driven shaft for said print roll, a rotary driving shaft, a gear train operatively connecting said driven shaft to said driving shaft, said gear train

5 including a shiftable reverse gearing and an axially adjustable worm having a worm wheel meshing therewith; whereby said print roll may be driven in either of opposite directions for the same direction of rotation of said driving shaft, and independently of the direction in which it is driven may be operatively angularly adjusted relative to said driving shaft.

10 21. A drier for a web having elongated drying means in opposed spaced relation to form a space through which the web is passed, and means for supporting the moving web at one or the other side thereof while passing through said space.

15 22. A drier according to claim 21 in which either drying means may be operated to the exclusion of the other, the means for supporting the moving web having provision for supporting it exclusively at its side adjacent the drying means which is inoperative.

LEROY Q. PRESBY.
